TELEPHONE DIAL LOCK

Filed Nov. 30, 1929

FIG. 1

FIG. 2

FIG. 3

FIG. 4

FIG. 5

INVENTOR:

I. Greenberg

UNITED STATES PATENT OFFICE

IRVING GREENBERG, OF BROOKLYN, NEW YORK

TELEPHONE DIAL LOCK

Application filed November 30, 1929. Serial No. 410,719.

My present invention relates to the telephone instruments equipped with a dial calling system and to a device for preventing the operation of said dial.

The main object of the invention is to provide a locking device that is easy to attach to a telephone instrument and that is simple to operate.

In carrying out my invention I provide a supporting member carrying the locking mechanism and having means for attaching to the telephone instrument, and a rotating arm supported on the above assembly, and arranged to engage a hole in the dial disk, and prevent its movement.

Figure 1 is a vertical longitudinal section through the device, taken on line 6—6 of Figures 2, 3 and 4, and shows the key in position for unlocking.

Figure 2 is a side elevation of the device as it is attached to a telephone instrument.

Figure 3 is a horizontal section through the device, taken on line 7—7 of Figures 1, 2 and 4 and shows its relation to the dial of the telephone instrument.

Figure 4 is a cross section, taken on line 8—8 of Figures 1 and 3, showing the arm in the locking position.

Figure 5 is a cross section, taken on line 8—8 of Figure 1 and 3, showing the arm in the unlocked position.

The telephone instrument to which this device is attached is indicated on the drawings by dotted lines, and consists of the pedestal 9, the base 10, the dial support 11, the dial 12, and the dial holes 13.

The locking device consists of a main supporting member 20, a latch 30, a lock 40, and rotating arm 50.

The supporting member 20 has a cylindrical depression 21 lined with the felt 22 and of such radius as to fit snugly around the telephone pedestal 9.

The projecting portion of member 20 is rounded to form in combination with the lock, a trunnion for the support of the rotating arm 50.

A band 60 lined with felt 61 is provided to encircle the telephone pedestal 9, and is

secured to the supporting member 20 by the screws 62 and 63.

The ends of this band 60 are arranged to fit under the sleeve 51 of the rotating arm, and are arranged so that the end screw 62 is attached during the assembly of the device, while the screw 63 is attached when the device is applied to the telephone.

For this purpose a cut 52 is made in the rotating arm sleeve 51 in such a position that when the arm is unlocked as in Figure 5, this cut is opposite the screw 63, and permits its attachment; when the rotating arm is locked this cut 52 is in the position shown in Figure 1, and it is therefore impossible to remove the device from the telephone.

To allow securing the band 60, under the sleeve 51, depressions 23 are provided at each side of supporting member 20.

The free end of the supporting member 20 is provided with projecting lugs 24, 25, and 26 intended to act as spacers and form the latch housing. A latch race 28, and spring housing 27 are also provided in member 20.

The latch 30 is actuated by the expansion spring 31 engaging hole 32, and is disengaged by the action of the lock cam 41 on the flange 33, integral with latch 30, as shown in Figure 5.

The lock shown is of the standard pin tumbler type although it is possible to use with this device a sliding disk or other type of lock.

This lock comprises the customary pin chambers and pins 42, the rotating plug 43 to which is secured the cam 41 and key 44.

This lock is secured to the supporting member 20 by the screws 45, 46 and 47.

The arm 50 is integral with the supporting sleeve 51, and rotates on the trunnion formed by the assembly of member 20 and lock 40.

The arm 50 is hollowed out at 53 to form a keeper for the latch 30, and the upper part of this recess is flanged as at 54, to engage the end of the spring 56.

The periphery of the projecting lugs 24, 25 and 26 is reduced so as to form a channel for the spring 56.

This spring 56 is of the expanding spiral

form with one end hooked over lug 25, and the other end hooked over flange 54, and is intended to bring arm to position 5 when unlocked.

15 A projection 55 is provided at the side of the arm 50 designed to engage the top of the support 20 and arrest the rotation of the said arm 50.

The device as described and assembled 10 when attached to the telephone will occupy the position shown on drawings, with the arm 50 as shown by dotted lines at 57 in Figure 2.

In this position the telephone dial can be 15 used with perfect freedom.

When it is desired to lock the telephone 20 against unauthorized users the arm 50 is turned down as shown in Figures 2, 3 and 4, when the extreme end 58 will enter the hole 13 of the dial 12 and prevent its rotation.

It is held locked by the latch 30, actuated by the spring 31 entering the depression 53 of the arm 50.

25 To unlock the device and release the dial for use, the key 44 is inserted in the lock 40, and if it is the proper key it will permit the plug 43 to turn.

The plug 43 and the cam 41 attached 30 thereto, is normally in the position shown by dotted lines in Figure 4.

When the cam 41 is turned to the right as shown in Figure 5 it presses against the flange 33 of the latch 30 and slides same out 35 of engagement with the keeper 53 in the arm 50 which, under the expanding action of the spiral spring 56 will swing up to the position indicated in Figure 5.

The device as shown can be made of various 40 metals, the lock may be an adaptation of any one of several different types, the details may be changed to fit various types of telephones without changing the scope and purpose of this invention.

45 I therefore do not wish to be restricted to the exact details of construction or sections shown or described.

Having thus described my invention, what I claim and desire to secure by Letters Patent is:

50 1. In a device of the character described, the combination with a dial telephone of a supporting member clamped to the pedestal of the telephone and disposed alongside of the dial; an arm for engaging and locking the dial of the telephone mounted rotatably upon the said supporting member and mechanism for locking and unlocking the said rotating arm for the purposes set forth 55 herein.

60 2. In a device of the character described, the combination with a dial telephone of a supporting member clamped to the pedestal of the telephone and disposed alongside the dial thereof; a rotating arm mounted upon

said supporting member and arranged to engage the dial and prevent its rotation; mechanism for maintaining the locked position of the dial and thereby prevent the removal of this device from the telephone and mechanism for releasing said rotating arm and directing same to a vertical position alongside the telephone pedestal thereby permitting an unobstructed view of the dial and the free operation thereof.

65 3. In a locking device for a telephone dial, a supporting member clamped to the pedestal of the telephone to form a trunnion for a dial locking arm, spring actuated and rotatably mounted thereon; a spring actuated latch disposed in a latch race upon said supporting member and engaging a keeper within said rotating arm; a lock secured to the said supporting member having a cam for actuating the said latch to release the spring actuated locking arm and permit it to rotate to a vertical position, freeing the telephone dial for its normal use; and mechanism for preventing the removal of the device when the dial is locked.

70 4. In a locking device for a telephone dial, a supporting member secured to the telephone pedestal and disposed alongside of the dial having means for clamping to said pedestal and prevent the removal of the device when the dial is locked; an arm rotatably mounted upon said supporting member through an integral sleeve entirely enclosing the mechanism therein; a spring disposed within said sleeve to maintain the said arm in a vertical position; a lock secured to said supporting member and disposed within said rotating arm sleeve; a cam actuated by said lock and arranged to engage a spring actuated latch disposed within said sup-

75 porting member; a keeper provided within the rotating arm arranged to be engaged by said latch when said arm is rotated into engagement with a finger hole of the telephone dial to prevent the rotation of said dial; and means for actuating the lock and latch to release the rotating arm for its return to the vertical position and permit the normal operation of the telephone dial.

80 IRVING GREENBERG.
